[57] CLAIM

A telephone base station, as shown and described.

DESCRIPTION

FIG. 1 is a perspective view of a telephone base station showing our new design, wherein the base station has its antenna in a lowered position;

FIG. 2 is a top plan view thereof;

FIG. 3 is a right side view thereof;

FIG. 4 is a left side view thereof;

FIG. 5 is a rear elevational view thereof;

FIG. 6 is a front elevational view thereof;

FIG. 7 is a bottom plan view thereof; and

FIG. 8 is a partial rear view thereof with the antenna in a raised position.

FIG. 1

FIG. 8
